AUTOMATIC FEED FOR DRILLS

Arthur E. Sherman, Detroit, Mich., assignor to
 Briggs Manufacturing Company, Detroit, Mich.,
 a corporation of Michigan

Application February 28, 1944; Serial No. 524,342

3 Claims. (Cl. 77—32)

This invention relates to pneumatic tools, and more particularly to pneumatically-operated manually-controlled drills.

In the present state of the art, it has been found desirable both from economic and production standpoints to use portable air-operated tools for drilling holes in the various places required in the parts which are to be assembled into a finished structure. Particularly is this so where the parts are of comparatively large size and irregular shape so that the design and construction of a drilling machine not utilizing portable drills would entail high tooling costs and initial delay in production. One of the disadvantages of the use of portable drills is that accuracy is dependent upon the skill and attentiveness of the human operator with the result that the drill holes are often misaligned. Furthermore, the feed of a portable drill depends upon the pressure applied by the operator, which if too great may result in damaging the work or the drills and if too small will result in lessened production.

One of the objects of my invention is to provide a pneumatically-operated tool of the portable type with a pneumatically-operated feed mechanism.

Another object is to provide such a tool with means by which the operator may quickly mount the same in a fixture for aligning the tool with the work.

These and other objects are accomplished by the construction hereinafter more fully described and illustrated in the accompanying drawing, in which

Figure 1 is a side view of the improved air drill shown in relation to the aligning fixture and a work piece;

Figure 2 is a longitudinal section through the feeding mechanism;

Figure 3 is a transverse section on the line 3—3 of Figure 2.

Referring to the drawing, 10 represents generally a portable air drill having a main body portion 11 containing a suitable air-operated motor of any suitable type and indicated generally by the reference character 11'. At the forward end of the body there is a rotatable chuck 12 for holding a drill 13, while at the opposite end of the body there is threadedly secured thereto a housing 14 having the pistol grip handle 15 depending therefrom.

Extending lengthwise of the handle 15 is a main air passageway 16 communicating with a trans-

verse passageway 17 leading to the air motor within the body 11. 18 is a valve longitudinally slidable within a lock nut bushing 19 threadedly secured at 20 to the handle and having a head 21 sealingly engaging the handle by means of a gasket 22. The bushing has the diametrically opposed openings 23 which are normally closed by the cylindrical portion 24 of the valve. The valve is maintained in closed position by a spring 25 and can be moved to open position by manual pressure on the button which moves the valve against the action of the spring to bring the annular groove 26 in the valve into alignment with the openings 23. An inlet opening 27 at the bottom of the handle may be suitably connected to a source of air pressure, not shown.

The main passageway 16 communicates through passageways 28 and 29 in the housing 14 to a small port 30 leading into the longitudinally extending cylinder 31. This port is adjustably controlled by a needle valve 32 threadedly engaging the housing and secured in adjusted position by a lock nut 33. Within the cylinder 31 there is a piston 34 having an annular packing member 35 secured thereto by means of a nut 36 on the central rod 37. The inner end of this rod has an enlarged head 38 and a projecting portion 39 of smaller diameter. A sleeve 40 surrounds the head 38 and extends longitudinally in the cylinder 31 through an opening in the threaded cap 42 which closes the rear end of the cylinder. A coil spring 44 surrounds the sleeve 40 and serves to normally urge the piston 34 to the left, as shown in Figure 2. Within the sleeve 42 is a slideable rod 45 having a projection 46 of smaller diameter on its inner end. A coil spring 47 is arranged within the sleeve surrounding the projections 39 and 46 respectively. The rod 45 extends through the sleeve 40 and is retained within the sleeve by a retainer ring 43 which engages the annular shoulder 48 on the rod 45. At the outer end of the rod 45 there is a projection 49 of smaller diameter which is adapted to enter a recess or aperture 50 in a suitably arranged backing bracket 51.

The portable air drill, as hereinbefore described, may be used for accurately drilling a work piece 52 by providing adjacent the work a guiding bracket 53 having a bushing 54 therein of suitable size to receive the drill 13. The guiding bracket 53 is in fixed relation to the backing bracket 51 with the aperture 50 thereof in alignment with the bushing 54 to direct the drill in the desired direction with respect to the work 52.

The operation of the device is as follows. The

operator first inserts the small end 49 of the rod 45 in the aperture 50 of the backing bracket 51 and then moves the portable drill 10 rearwardly which is permitted by the compression of the small spring 47. The drill 13 may then be inserted within in the bushing 54 whereupon the spring 47 will urge the device forwardly so that the drill engages the work piece. The operator then depresses the button 25 which permits air pressure to pass through passageways 16 and 17 into the air motor and rotate the drill. At the same time air from passageway 16 is by-passed through passageways 28, 29 and 30 into the cylinder 31. As the pressure builds up in the cylinder, the piston 34 is moved rearwardly within its cylinder until the lost motion between the rod 45 and sleeve 40 is taken up by the contact of the ends of projections 46 and 39. Thereafter, since the rod 45 rests against the fixed abutment of the backing bracket 51, additional pressure built-up within the cylinder causes the entire drill assembly to move forwardly and feed the drill into the work piece. The rate of feed may be controlled by the adjustment of the needle valve 32. As soon as the drilling operation is completed, the operator releases the control button 25 and manually withdraws the drill through the bushing 54 by pressing the drill assembly rearwardly and then removes the rod 45 from the backing bracket, whereupon the sequence of operations is again repeated with the tool arranged in position for drilling the next hole.

What I claim as my invention is:

1. In a pneumatically-operated portable tool, the combination with a casing, a tool rotatably supported therein and a pneumatically-operated motor for said rotatable tool, of a cylinder arranged longitudinally within said casing, a piston in said cylinder, a member projecting through said casing, a telescoping member between said projecting member and said piston providing a limited

lost motion connection therebetween, and means for connecting said cylinder to a source of pneumatic pressure to cause relative longitudinal feeding movement between said projecting member and said casing.

2. In a pneumatically-operated portable tool, the combination with a casing, a tool rotatably supported therein and a pneumatically-operated motor for said rotatable tool, of a cylinder coaxial with said rotating tool, a piston in said cylinder, a sleeve connected to said piston and projecting rearwardly through said casing, a rod slidable within said sleeve, a spring within said sleeve between the inner end of said rod and said piston, a spring surrounding said sleeve between said piston and said casing, means for limiting the longitudinal movement between said rod and sleeve, and means for connecting said cylinder to a source of pneumatic pressure to cause relative longitudinal feeding movement between said projecting member and said casing.

3. In a pneumatically-operated portable tool, the combination with a casing, a tool rotatably supported therein and a pneumatically-operated motor for said rotatable tool, of a cylinder coaxial with said rotating tool, a piston in said cylinder, a sleeve connected to said piston and projecting rearwardly through said casing, a rod slidable within said sleeve, a spring within said sleeve between the inner end of said rod and said piston, a spring surrounding said sleeve between said piston and said casing, means for limiting the longitudinal movement between said rod and sleeve, a handle extending transversely of said casing having a fluid passageway connected to said motor and to said cylinder, a manually-operated valve in said passageway, and an adjustable metering valve between said fluid passageway and said cylinder.

ARTHUR E. SHERMAN.
